UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

LIGHTING AND IGNITION SWITCH.

Application filed November 12, 1924. Serial No. 749,442.

This invention relates to lighting and ignition switches for use on automobiles and the like and has for its object to simplify the construction to increase its efficiency and durability and at the same time reduce the cost of manufacture.

Another purpose of the invention is to utilize sheet metal and insulating fiber stampings as far as possible in the manufacture of the switch with reliance on coil springs to effect contact engagements and detents for the different switch positions.

Another object of the invention is to provide a multiple contact member which is flexible and yieldingly carried by its actuator with springs behind its contact parts for causing them to independently bear upon the terminal head.

With the above objects in view the invention consists in the lighting and ignition switches as herein claimed and all equivalents.

Referring to the accompanying drawings, in which like characters of reference indicate similar parts in different views,

Fig. 1 is a front view of a lighting and ignition switch constructed in accordance with this invention;

Fig. 2 is a longitudinal sectional view thereof;

Fig. 3 is a rear view thereof showing the arrangement of the terminal head;

Fig. 4 is a similar view showing a slightly modified arrangement of the terminal head;

Fig. 5 is a transverse sectional view thereof;

Fig. 6 is a similar view showing the ignition switch driver in elevation;

Fig. 7 is a rear view of the switch with the terminal head removed;

Fig. 8 is a similar view with the switch members also removed and the lighting switch driving ring broken away;

Fig. 9 is a rear view of the switch-case;

Fig. 10 is a longitudinal sectional view of the switch showing a modification thereof;

Fig. 11 is a transverse sectional view thereof;

Fig. 12 is a detail view of the spring ring for the switch handle;

Fig. 13 is a detail view of the spring washer for the switch handle;

Fig. 14 is a detail view of the mounting ear of the switch shown in Figs. 10 and 11; 55
Fig. 15 is a face view of the terminal head, and

Fig. 16 is a detail of the connection between the handle and driver ring.

In these drawings, 20 indicates a sheet 60 metal shell forming a shallow cylindrical switch-case with its end depressed and slotted to form a bearing for the switch members and to accommodate driving connection for them and centrally embossed or raised to provide a key guide bearing, as will be later described. The open end of the switch-case receives a disk of insulating material forming a terminal head 21 which may be detachably secured in place by 70 means of pins 22 projecting from its edge and fitting in bayonet slots in the edge of the switch-case, as shown in Figs. 2 and 5, or by having ears 23 on the edge of the switch-case extending through notches 24 in 75 its edge and bent over on the rear of the terminal head, as shown in Figs. 10, 11 and 15.

A face plate 25 is secured to the front of the switch-case as by having its edges 80 turned down into bearing therewith and provided with tongues 26 passing through suitable openings in the switch-case and clinched therebeneath.

A handle member 27, preferably of sheet 85 metal, passes through an opening of the front plate 25 and has shouldered lugs 28 passing through slots 29 in the depressed end of the switch-case and engaging notches in the inner edge of a metal driving ring 90 30 which bears against the under surface of the end of the switch-case. The driver ring 30 has downwardly extending driving lugs 31 engaging notches 32 in opposite edges of a contact ring 33 of insulating material carrying spring-pressed contacts 34 bearing on the terminal head 21.

The contacts 34 consist of ball-shaped projections formed in a split-ring-like flexible metal contact member 35 which is loosely 100 fulcrumed and slidable upon pins 36 carried by the contact ring 33. There are four of these contacts 34, as shown, bearing with spring pressure against the terminal head and in different positions of the handle engaging in the depressions of the several con-

tact studs 37 thereof to establish electrical connection between them or in the detent recesses 38 formed in the face of the terminal head. The contact member 35 is preferably bent above its normal plane where it fulcrums on the pins 36 and is desirably reduced in width as at 39 between the two intermediate contacts to give greater flexibility.

Each of the contacts 34 is spring-pressed 10 toward the terminal head by having a coiled spring 40 seated in the cavity above it and in a recess or countersunk seat in the bottom of the contact ring 33, as best seen in Fig. 2. The ends of the pins 36 are preferably 15 headed to prevent the removal of the contact member from the contact ring when the parts are unassembled and, to prevent contact of their upper heads with the driver ring 30, a ring 41 of thin insulating material is held 20 between rings 30 and 33 by the driving lugs 31.

Within the handle is a key guide 42 with its reduced ends mounted to turn in the handle and in the dome-shaped raised portion 25 of the switch-case end.

A dished driver disk 43 has a central opening into which the reduced lower end of the key guide 42 fits and at its edge there is an upturned stop lug 44 traveling in an arcuate 30 slot 45 of the end of the switch-case, while downwardly turned driving lugs 46 engage notches in the edge of a contact disk 47 of insulating material which lies approximately in the plane of the contact ring 33.

35 A contact member 48 is loosely fulcrumed and slidably mounted on a pair of pins 49 on the contact disk 47 corresponding with the pins 36 and is provided with a pair of contacts 50 in a line at right angles to the 40 line joining the pins and corresponding with the contacts 34 with coiled springs 51 behind them corresponding with the springs 40 and adapted to engage with contact studs 52 in the terminal head.

45 A spring washer 53 is confined between the shoulder of key guide 42 and the handle member 27 to take up play between said key guide and its bearings and to hold it from turning.

50 A key 54 entered through the central slot of the key guide engages its end in a U-shaped sheet metal pocket 55, which is let into a slot in the center of the contact disk 47 with oppositely extending flanges bearing 55 thereon. A disk of insulation material 56 is held between the driver disk 43 and said disk 47. The arched central portion of the switch-case end and the driver disk 43 not only have a central circular opening to receive the end 60 of the key guide 42 for centering the switch member, but also have a slot through said opening to register with the key slot of the key guide 42 to admit the key to the pocket 55. There are notches in the edges of the 65 key and one pair of these notches register

with the end wall of the switch-case when the key is fully inserted. When the key is first inserted and bears in the pocket 55 the notches are not in register with the end of the switch-case and the key cannot be turned, 70 making it necessary to press the key all the way in and, in so doing, slightly depress the contact disk 47 against the action of its springs. However, when the springs are so compressed and the key is turned, the shoulders of the key formed by said notches are held with the pressure of the springs against the end wall of the switch-case and so the key is held from rattling and prevented from dislodgment. In turning the key its 75 engagement with the driver 43 compels the contact disk 47 to turn also and make or break the connection between the contact studs 52 to control the ignition circuit of the automobile. As such movement can only be effected by means of a key of the required shape, theft or unauthorized use of the automobile is prevented by removing the key.

The turning of the handle 27, which may be accomplished whether the key is present 80 or not, causes a corresponding turning of the driver ring 30 by reason of the engagement of its lugs 28 therewith and the ring, by the engagement of its lugs 31 with the contact ring 33, causes it to turn and change the connections made by the contacts 34 with the contact studs 37 to control the lighting circuit of the automobile and effect the various usual changes thereof. The driver ring 30 forms a metal to metal bearing with the end 85 of the switch-case to take the wear and the thrust of the springs 40.

The operating parts are all held in place with spring pressure, avoiding any rattle or unintended change in position. The construction and arrangement of the contact members is such that each contact is forcibly and independently held in bearing with the terminal head to secure a firm contact engagement with the terminal studs to make 90 efficient electrical connection therewith and said contacts of each contact member, being pressed out of the same piece of metal, are, of course, in ideal electrical communication 95 with one another.

The mounting of the contact member 35 permits it to yield bodily and also to warp and bend and to fulcrum on the driving pins 36 to adapt itself to the irregular travel of its contacts 34 on the surface of the terminal head so that all of the contacts may be held in firm bearing engagement with the terminal head at all times. The flexible contact member 35 loosely pivotally mounted on the driving pins 36, and urged by coiled springs 100 behind the contacts, is positively driven by the turning of the handle, and assures an efficient electrical connection with the contact studs.

105 On the rear of the terminal head the con-

tact studs may be connected as desired, some of such connections being shown in Figs. 3 and 4.

In Figs. 10 and 11 a modification of the invention is shown, wherein the handle member 27, instead of driving the contact ring 33 by means of the driver ring, has a direct connection for this purpose consisting of lugs 57 engaging in notches on the inner surface 10 of the contact ring 33. Instead of the handle member having clinched shouldered lugs 28, it has an outwardly bent flange 58 engaging beneath a spring ring 59 shown in detail in Fig. 12, which is clamped between the face-15 plate 25 and the switch-case. The inner edges of the spring ring 59 are split, as shown in Fig. 12, to enable it to bear with spring action upon the flange of the handle member to hold the parts against loose movement. In this construction also, instead of forming attaching lugs or screw-ears 60 by cutting them from the switch-case and then doubling them upon themselves and screw-threading them, as shown in Figs. 1 and 2, 20 such ears 61 are formed by extensions on the edge of the face-plate 25.

What I claim as new and desire to secure by Letters Patent is:

1. In a switch, a switch-case having a closed end, a handle member mounted to turn on the end of the switch-case, a key guide positioned between the handle and the end of the switch-case and mounted to turn therein, a contact member mounted to turn 35 on the end of the key guide, and a key fitting in a slot of the key guide and engaging the contact member for turning it.

2. In a switch, a switch-case having a closed end, a handle member mounted to turn on the end of the switch-case, a key guide between the handle member and the end of the switch-case mounted to turn therein, a driver mounted to turn on the key 40 guide, a key fitting in a slot of the key guide and engaging the driver for turning it, and a contact disk carried by the driver.

3. In a switch, a switch-case having a closed end, a handle member mounted to turn on the end of the switch-case, a key 50 guide between the handle member and the end of the switch-case and mounted to turn therein, a driver mounted to turn on the end of the key guide, a lug on the driver entering a slot in the end of the switch-case to limit the movements of the driver, a key fitting in 55 a slot of the key guide and engaging the driver for turning it, and a switch member carried by the driver.

4. In a switch, a switch-case having a closed end, a handle member mounted to turn on the end of the switch-case, a key guide between the handle member and the end of the switch-case and mounted to turn 60 therein, a spring-pressed switch member, a key fitting in a slot of the key guide and a

slot in the end of the switch-case and engaging with the switch member before it is fully inserted, there being notches in the key to engage the end of the switch-case when the key is turned while fully inserted 70 whereby the switch member is depressed by the key and the key is held with spring pressure in bearing with the end of the switch-case.

5. In a switch, a switch-case having a closed end, a handle member mounted to turn on the end of the switch-case, a key guide between the end of the switch-case and the handle and mounted to turn therein, a spring-pressed switch member mounted to 75 turn on the key guide, and a key fitting in a slot of the key guide and engaging the switch member to depress it against its spring pressure and having a shoulder to engage the end wall of the switch-case when 80 the key is turned.

6. In a switch, a switch-case having a closed end, a key mounted to turn thereon, a key guide mounted to turn between the handle member and the end of the switch-case, a driver mounted to turn on the key guide, a spring-pressed switch member carried by the driver, and a key fitting in a slot of the key guide and in a slot in the 85 driver and engaging the switch member for depressing it against its spring action, there being a shoulder on the key for engaging the end wall of the switch-case when the key is turned while the switch member is depressed.

7. In a switch, a switch-case having a closed end, a handle member mounted to turn thereon, a key guide mounted to rotate between the handle member and the switch-case end, a driver mounted to rotate on the key guide, a spring-pressed switch member carried by the driver, a flanged U-shaped metal pocket fitting in an opening of the switch member, and a key fitting in a slot of the key guide and in a slot of the switch-case end and in a slot of the driver and seated in the pocket for depressing the switch member against its spring action and having a shoulder for engaging the end of the switch-case when the key is turned while the switch member is depressed.

8. In a switch, a switch-case having a slotted closed end, a switch handle mounted to turn on the end of the switch-case and having shouldered lugs extending through the slots, a sheet metal driver ring having notches in its inner edge into which the shouldered lugs are clinched, driving lugs at the outer edges of the driver ring, and an insulation contact ring engaged by said lugs.

9. In a switch, a switch-case having a closed end provided with slots, a switch handle mounted to turn on the switch-case end and provided with lugs passing through 130

the slots, a sheet metal driver ring within the switch-case bearing on the switch-case end and having said lugs clinched thereto, driving lugs on the driver ring, and a spring-pressed contact ring of insulating material bearing on the driver ring and engaged by said driving lugs.

10. In a switch, a switch member mounted to turn, a pair of pivot pins fixed thereon, a sheet metal contact member in the form of a split ring loosely pivoted on the pivot pins, contacts formed on the contact member, springs behind the contacts bearing on the switch member, and a terminal head on which the contacts bear and having contact studs engaged thereby, said contact member being flexible to permit each contact to independently follow irregularities in the surface of the terminal head.
15. 11. In a switch, a contact ring mounted to turn, pivot pins carried thereby, a split ring contact member of flexible sheet metal loosely pivoted on the pivot pins and having pressed

out therefrom rounded projections forming contacts, coiled springs seated in each of the contacts and in the contact ring, and a terminal head against which the contacts bear provided with recessed contact studs engaged by the contacts.

20. 12. In a switch, a switch-case having a closed end, and attaching ears formed by strips of metal cut from the switch-case near the closed end and folded on themselves and projecting from the switch-case in the plane of the closed end and provided with screw-threads.

25. 13. In a switch, a switch member, headed pivot pins thereon, a sheet metal contact member loosely and pivotally mounted on the pivot pins, a pair of contacts formed on the contact member in a line at right angles to the contact pins, and springs confined between the contacts and the switch member.

30. 35. In testimony whereof, I affix my signature.

EDWARD N. JACOBI.
